UNITED STATES PATENT OFFICE

CHARLES E. PAGE, OF LOS ANGELES, CALIFORNIA

DESIGN FOR A HANDLE FOR COFFEE MAKERS

Application filed July 22, 1932. Serial No. 44,415. Term of patent 3½ years.

To all whom it may concern:

Be it known that I, CHARLES E. PAGE, a citizen of the United States, residing at Los Angeles, county of Los Angeles, and State of California, have invented a new, original, and ornamental Design for a Handle for Coffee Makers, of which the following is a specification, reference being had to the accompanying drawing.

Figure 1 is a side view of the handle showing my new design,

Figure 2 is an edge view thereof, and Figure 3 is a top view thereof.

The handle of the present invention is a complete article in itself, and is designed to be made and sold for use upon various types of coffee makers.

I claim:

The ornamental design for a handle for coffee makers, as shown and described.

CHARLES E. PAGE.
